UNITED STATES PATENT OFFICE.

EDWARD HUBER AND HENRY M. BARNHART, OF MARION, OHIO.

CAR-COUPLING.

SPECIFICATION forming part of Letters Patent No. 295,763, dated March 25, 1884.

Application filed November 27, 1883. (No model.)

To all whom it may concern:

Be it known that we, EDWARD HUBER and HENRY M. BARNHART, citizens of the United States, and residents of Marion, in the county of Marion and State of Ohio, have invented certain new and useful Improvements in Car-Couplings; and we do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical sectional view of our improved car-coupling, showing it ready for coupling. Fig. 2 is a similar view showing it coupled. Fig. 3 is a similar view showing the pin drawn up and resting with its point in its recess in the act of uncoupling; 20 and Fig. 4 is a cross-section on line $x-x$, Fig. 2.

Similar letters of reference indicate corresponding parts in all the figures.

Our invention has relation to that class of automatic car-couplings in which the pin, when uncoupled, is supported by a projecting lip upon a spring-block sliding in the recess in the draw-head and adapted to be pushed back by the coupling-link; and it consists in the improved construction and combination of parts of such a coupling, in which the perforation for the coupling-pin has a recess at its upper end for the reception of the point of the pin, and in which the spring-block has an upwardly-projecting lip sliding in a longitudinal slot in the draw-head, guiding the block and pushing the pin out of its recess when forced forward by the spring, as herein-after more fully described and claimed.

In the accompanying drawings, the letter A indicates the draw-head, which is of the usual construction, having the usual vertical perforation, B, for the reception of the pin C, while its recess D is extended rearward, forming a perforated bearing, E, in which the rearwardly-extending bar F of the sliding spring-block G slides, and against which the rear end of a spring, H, wrapped around the bar, bears, the forward end of which spring bears against rear side of the block, forcing it forward. 50 The upper forward edge of the sliding block

forms a forwardly-projecting lip, I, upon which the point of the pin rests when drawn up, and the upper side of the block is provided with a longitudinal upwardly-projecting lip, J, which slides in a longitudinal slot, K, in the upper side of the recess in the draw-head. The rear side of the upper portion of the vertical perforation for the pin forms a recess, L, inclined slightly rearward with its lower end, and the longitudinal slot, which is narrower than the recess, enters the lower end of the same. When the cars are brought closer together for uncoupling, the link will force the spring-block rearward, and the pin may be raised and placed with its end in the recess, its upper end pointing forward; and in withdrawing the link the spring-block will slide forward, pushing the point of the pin forward out of the recess with the upwardly-projecting lip, when the point of the pin will rest upon the forwardly-projecting lip; and it will be seen that when the link again is introduced into the draw-head the sliding spring-block will be forced rearward, allowing the pin to drop in the perforation and through the link, coupling again. It will also be seen that the upwardly-projecting lip will serve as a guide for the sliding spring-block, besides serving to push the point of the pin forward, and that by having the recess in the perforation for the pin the pin may be withdrawn and be held in its raised position while the link is holding the spring-block back, which cannot be done in couplings of this class having only a forwardly-projecting lip upon the spring-block, which can only hold the pin raised when the link is out of the draw-head, consequently necessitating the presence of the brakeman at the coupling exactly at the moment when the cars are to be uncoupled.

Having thus described our invention, we claim—knowing that couplings have been made with sliding spring-blocks having forwardly-projecting pin-supporting lips—as follows:

The combination of a draw-head having the usual vertical perforation for the pin, provided at the rear side of its upper portion with a recess, and having a longitudinal recess forming a narrower slot at its upper side, the forward end of the said slot entering the lower

end of the recess in the pin-receiving perforation, a spring-actuated block having a forwardly-projecting lip and an upwardly-projecting lip upon its upper side, and a common 5 coupling-link and pin, as and for the purpose shown and set forth.

In testimony that we claim the foregoing as

our own we have hereunto affixed our signatures in presence of two witnesses.

EDWARD HUBER.
HENRY M. BARNHART.
